CORRELATING MEANS FOR CEILING OR PARTITION PANELS

Application filed June 10, 1929. Serial No. 369,599.

This invention relates to the structural association of plaster board or similar fiber partitioning panels which are now so much used for both wall and ceiling construction, and has for its object an improved organization of parts by means of which the several sections of board which generally come in stock sizes, and are designed to be positioned in the same plane with one another, may be firmly supported with relation to one another, and may have made strongly adherent thereto a coating or surface finish of plaster, stucco, or the like. By the use of my improved correlating means I am enabled to reduce to a minimum the appearance in the finished plaster surface of ridges, depressions, or cracks correspondingly positioned to the line of union between the plaster boards or panels, which is otherwise likely to occur because of the surfacing while plastic sinking more or less into the cracks or surface of the meeting edges of adjacent boards.

In the drawings:

25. Figure 1 is an elevational view of a ceiling structure wherein my invention is embodied, shown suspended as by means of wires from horizontal structural beams, whether wood or metal.
30. Figure 2 is an elevational view, partly in section showing my improved construction as applied to a wooden joist by nailing or similar means.

35. Figure 3 is a perspective of my improved correlating means applied to fragmentary adjoining portions of two plaster board units.

40. Figure 4 is a partly sectional elevational view thereof positioned in rather close relation beneath a structural beam.

45. Figure 5 is a perspective similar to Figure 3, but showing the provision of structurally integral expanded metal flanges from the edges of the overbent sections of my improved correlating means, designed to constitute an additional adhering or binding means with an applied coat of plaster.

50. Figure 6 is a sectional elevational view taken along the line 5-5 of Figure 4, and

looking in the direction of the arrows there shown.

Figure 7 is a perspective similar to Figures 3 and 5, but showing a slightly modified form of correlating web.

Figure 8 is a sectional elevational view taken along the line 8-8 of Figure 7, and looking in the direction of the arrows there shown.

At A in Figure 1 is shown a horizontal structural beam of any desired material, from the under side of which hang wires B, by means of which subordinate beams C are held in desired spaced relation from the main beam A. At intervals along the under side of the beam C are suspended channel bar elements D, or in place thereof, if desired as shown in Figure 2, wooden joists E, from the under flange or faces of which the correlating sheet metal web herein disclosed may be supported, in the case of the channel bars D by means of wires F which pass through the holes G; or in the case of the wooden joist E a correlating sheet metal web is secured thereto by nails H passing through the holes G.

As brought out particularly in the perspective figures, this correlating element, whether corrugated or plain, is in the form of a central web J (or the plain web K shown in Figure 7), from each of whose marginal edges as regards its vertically positioned section there project overbent flange pieces or sections, as M and N, with either plain or serrated edges as indicated at T and V respectively, these being preferably spaced from one another and arranged in staggered relation, that is, for example, the overbent sections M not being positioned directly opposite the overbent sections N appurtenant to the upper edge of the central web J. It will thus be obvious that viewed lengthwise this correlating sheet metal web piece as a whole is suggestive of a capital H resting on its side (note Figures 4, 6, and 8 particularly), whereas a section taken through the central part and through such parts of the overbent flange pieces M and N as may overlap as regards their positioning lengthwise of the web piece as a whole the cross-sectional effect

would be zig-zagged in the shape of a more or less right angled capital **Z**. The sheet metal structure thus constituted is designed to have positioned, in the channels thus formed by its overbent edge sections **M** and **N**, the edges of panels or partition boards, as **P** and **Q**, which are thus firmly held in adjacent though not actually marginally contacting position, being spaced from one another by the web portion **J** (or **K**).

In some instances either the plain overbent sections such as are illustrated in Figure 7 or the corrugated overbent sections such as are illustrated in Figure 3, prove adequate to alone effect a binding interlock with an applied plastic coating when the latter has dried. In other cases, however, I find it advisable to provide extensions along the free or outer edges of the overbent marginal flanges in the form of an expanded metal edging unit such as is shown at **L**, and which it will be obvious will afford a greater surface for purposes of interlock with the plastic coating **R** when applied.

It will thus be obvious that as to either of the forms of correlating member shown in Figures 3, 5, or 7, all preferably of sheet metal of appropriate gauge, there is not only constituted an efficient mechanical union of as many panels as may be needed, but that the space between each, in which the central web of the correlating member lies, is so protected and filled, not only by it but by the overengagement onto the marginal edges of the surface of these panels, of the overbent sections, as **M** and **N**, that very little of an applied plastic coating, as **R**, can sink therewith and thus form troughs or cracks or depressions in the hardened, finished surface thereof. Such of the plastic coating as may make its way into the web-occupied space between the edges of adjacent boards, particularly if the central web portion is of the corrugated character indicated at **J** in Figure 3, tends to form, when hardened, key projections, of course integral with the rest of the plaster body, which actually strengthen and increase the degree of the hold of the latter upon the built up and correlated base structure herein described.

What I claim is:

Means for effecting the aligned correlation of partitioning panels and for facilitating the adherence thereto of an applied plastic coating, comprising a plurally crenelated sheet metal web having alternately right-angularly overbent portions adapted to overengage the marginal edge of one surface or the other of a panel whose bordering edge is placed against the central part of the web, structurally integral extensions from said overbent portions having slotted portions between and about which an applied plastic surfacing may effect a space filling and superficially straight interlock when hardened,

and means for holding the panels and the interposed metal web in desired relative position to a supporting element.

In testimony whereof I sign this specification.

FRANK S. ROBINSON.
